UNITED STATES PATENT OFFICE.

FRANCISZEK KOWALSKI, OF PHILADELPHIA, PENNSYLVANIA.

PROPELLER.

1,228,787.

Specification of Letters Patent. Patented June 5, 1917.

Application filed October 16, 1916. Serial No. 125,878.

To all whom it may concern:

Be it known that I, FRANCISZEK KOWALSKI, a subject of the Czar of Russia, residing at Philadelphia, in the county of Philadelphia and State of Pennsylvania, have invented certain new and useful Improvements in Propellers, of which the following is a specification.

This invention relates to certain new and useful improvements in propellers.

The primary object of the invention is the provision of a propeller adapted for employment with either marine propulsion or aerial craft, the same being so arranged as to be easily repaired in the event that any portion thereof becomes damaged or destroyed.

A further object of the device is the provision of a propeller adapted for exerting a direct longitudinal movement to the member supplied thereby, this being accomplished by an arrangement of oppositely-positioned helical blade sections, each of the latter being formed of removable plates readily replaced or repaired as may be required.

With these general objects in view and others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—

Figure 1 is an elevational view of the device with the peripheral portion thereof broken away.

Fig. 2 is a side elevation of the same.

Fig. 3 is a perspective view of one of the removable plates detached, and,

Fig. 4 is a perspective view of a portion of the rim member employed.

Fig. 5 is an enlarged detail sectional view of a peripheral portion of the propeller, and,

Fig. 6 is a detail end elevation view of a portion of one of the blades illustrating the attaching means therefor, parts being broken away.

The present propeller broadly consists of a tubular hub 10 and oppositely-arranged separate blades 11 each being of the form of substantially one-half of a helix, it being noted that the adjacent edges of the said

blades are positioned in planes separated from each other. Each of the blades 11 is formed of a plurality of tapered plates 12 having their contacted inner ends provided with oppositely projecting base flanges 13. A mounting guide 14 is provided for the plates 12 being in the form of a strip substantially U-shaped in cross-section helically secured to the outer face of the hub 10 between the opposite ends thereof. One of the said guide strips 14 is preferably arranged at substantially opposite sides of the hub 10 into which guides, the bases 13 of the plates 12 are slidably fed during the assembling of the blades. Locking bolts 15 are carried by inwardly-extending flanges 16 of the guide strips 14 adapted for engaging the plate bases 13 having retaining plates in position with the said plates having their edges in contact with each other, it being understood that the flanges 16 of the guide strips overlie the plate portions 13.

Dove-tailed grooves 17 are provided in the curved outer enlarged ends or peripheral portions 18 of the plates 12 forming a continuous groove throughout the periphery of the blades when the plates are assembled. A locking strip 19 having a dove-tailed tongue 20 adapted to be slidably positioned within the blade grooves 17 is provided forming a binder for the plates which make up the separate blades. Hold-fast devices, such as screws 21 may be secured through the strip 19 engaging within plates 12 as illustrated in Fig. 5 of the drawing.

From this detailed description of the invention, it will be seen that a serviceable propeller is arranged in which the blades are formed of a plurality of plates 12 detachably connected together by the binding strips 19 while each plate is removably locked to one of the guide strips 14. By removing the locking strip 19 slidably from the outer edges of the plates 12, the said plates may be removed from the guide strips 14 upon releasing the locking bolts 15.

What I claim as new is:—

1. A propeller comprising a hub, substantially semi-helical guide strips secured to the outer face thereof, a plurality of blades having their inner ends removably secured within the said guide strips, said plates being tapered and having their outer enlarged ends of arcuate formation provided with dove-tailed grooves adapted for forming a continuous groove throughout the said plates.

when the latter are arranged in an edgewise engagement, and a locking strip for the said plates peripherally secured thereto removably positioned within the said grooves.

5 2. A propeller comprising a cylindrical hub, substantially U-shaped semi-helical guide strips arranged upon opposite sides of the hub connecting the opposite ends thereof, a plurality of plates having base

portions slidably arranged within the said 10 guide strips, locking means for the said base portions carried by the said strips, a removable locking strip peripherally mounted upon said plates, the said guide strips and plates carried thereby lying in separate 15 planes longitudinally of the hub.

In testimony whereof I affix my signature.
FRANCISZEK KOWALSKI.
